PAIR OF SPECTACLES

Bernard Lhospice, Saint-Denis, Seine, France, assignor to
Societe des Lunetiers, Cottet, Poichet, Tagnon & Cie,
Paris, France

Filed July 24, 1962, Ser. No. 71,031

Term of patent 3½ years

(Cl. D57—1)

FIG. 1

FIG. 1 is a front elevational view of a pair of spectacles showing my new design;

FIG. 2 is a rear elevational view thereof; and

FIG. 3 is a top plan view thereof.

The dominant features of my design reside in the portions shown in full lines.

The temple portions are shown broken away in FIG. 3 for convenience of illustration.

The drawing is stippled and lined to show contrast.

I claim:

The ornamental design for a pair of spectacles, as shown and described.
